UNITED STATES PATENT OFFICE.

JAMES SWAN, OF SEYMOUR, CONNECTICUT.

DESIGN FOR A TOOL-HANDLE.

SPECIFICATION forming part of Design No. 28,231, dated February 1, 1898.

Application filed December 3, 1897. Serial No. 660,707. Term of patent 14 years.

To all whom it may concern:

Be it known that I, JAMES SWAN, a citizen of the United States, residing at Seymour, in the county of New Haven and State of Connecticut, have invented and produced a new and original Design for Tool-Handles; and I do hereby declare the following to be a full, clear, and exact description of the same, reference being had to the accompanying drawing, forming a part thereof, in which the figure represents an elevation of a tool-handle embodying my design.

The leading feature of my design consists of a tool-handle having the surface of its gripping portion provided with concaved spiral grooves parallel with each other and oblique to the axis of the handle, the relatively high portions between the grooves following the circumferential curvature of the handle, im- 5 parting to said gripping portion the appear- ance of a spirally-grooved roll.

A denotes the gripping portion of the handle. The surface of the gripping portion is ornamented by a series of spiral grooves *b*, with relatively high portions *a* between said grooves, said relatively high portions following the circumferential configuration of the handle, the whole imparting to said gripping portion the appearance of a spirally-grooved roll, the grooves alternating with the relatively high portions. 25 30

What I claim is—

The design for a tool-handle substantially as shown and described.

In testimony whereof I affix my signature 35 in presence of two witnesses.

JAMES SWAN.
